UNITED STATES PATENT OFFICE.

ROBERT H. CLYMER, OF ANACONDA, MONTANA.

ADJUSTABLE DECK FOR STOCK-CARS.

1,118,108.

Specification of Letters Patent.

Patented Nov. 24, 1914.

Application filed May 11, 1911. Serial No. 626,530.

To all whom it may concern:

Be it known that I, ROBERT H. CLYMER, citizen of the United States, residing at Anaconda, in the county of Deerlodge and 5 State of Montana, have invented certain new and useful Improvements in Adjustable Decks for Stock-Cars, of which the following is a specification.

My invention relates to an improvement 10 for stock cars and particularly to a deck or platform mounted within the same and adjustable in a manner and for a purpose which will be subsequently pointed out.

It is my object to provide a deck of this 15 type which will double the capacity of the car.

Another object of my invention is to provide a deck which may be adjusted into position during the sheep season and which, 20 when the season is over may be lowered so as not to interfere with the other uses of the car.

A further object of my invention is to provide a deck which will be simple in construction, durable and economical of manufacture.

With the foregoing and other objects in view my invention consists in such details of construction and in the arrangement and 30 combination of parts as will be hereinafter more fully described and specifically pointed out in the appended claim.

In describing my invention in detail reference will be had to the accompanying 35 drawings in which like characters denote like or corresponding parts throughout the several views and in which,

Figure 1 is a horizontal sectional view of my invention. Fig. 2 is a side elevation of 40 my invention on the line 2—2 in Fig. 1, disclosing the deck in raised position and indicating, by dotted lines, the lowered position of the same. Fig. 3 is a side elevation of my invention on the line 3—3 in Fig. 1 disclosing the deck in lowered position and indicating, by dotted lines, the raised position of the same. Fig. 4 is a cross section of my invention on the line 4—4 Fig. 2. Fig. 5 is a sectional detail disclosing a support in operative 45 position, and Fig. 6 is a detail disclosing a support in folded position.

Referring to the drawings 1 designates a stock car of usual construction. Plates 2 are countersunk in the floor of the car 1 into 50 which are stepped threaded shafts 3. The shafts 3 are angularly formed at their up-

per extremities for the reception of a wrench or suitable tool whereby turning of the same may be effected. Straps 4 are passed about the shafts 3 and secured upon the sides of the car for maintaining the shafts in an upright position close thereagainst. Fitted over and adapted to threaded engagement with the shafts 3, traveling nuts 5 are attached upon the outer of a plurality of 60 channel beams 6. Cross beams 7 are suitably secured across beams 6 thus forming the skeleton of my improved deck which may be strengthened by braces 8 of any adaptable form.

From the above it will readily be seen that this structure is snugly fitted into the interior of the car, as disclosed to advantage in Fig. 1, and is adjustable upon the shafts 3 through the medium of the traveling nuts 5. The provision of a suitable floor, laid upon this frame in a manner well known to the art, will be fully appreciated to complete a novel and highly useful adjustable deck. The disclosure thus far contains the 80 elements of a new and readily operable device for accomplishing the objects heretofore set forth. Yet, taking into consideration the enormous weight to which a structure of this character would be likely to be 85 subjected and the jarring resulting to the same from the motion of the car, the screw shafts 3 will be found to form but inadequate supports. For the purpose of sus-

taining the deck in secure operative position the following means have been devised. Rods 9 having therein apertures 10 are pivoted upon suitable bolts 11 within the downwardly turned flanges of the channel beams 6. Adapted to telescopic engagement with the rods 9, tubular standards 12 are provided with apertures 13. Suitable means may be passed through the registering apertures of said rods and standards to maintain the supports at any desired 90 adjustment.

Fig. 5 illustrates a support in operative position showing in dotted lines the folded position of the same and the curve described by the same when forced up between a channel beam where it snugly fits and is frictionally held. Fig. 6 discloses another advantageous view of this detail which is at right angles to Fig. 5 and shows the position taken by the support when folded and 100 placed within the beam.

The operation of my device may be con-

ducted as follows: When it is desired to raise the deck for the purposes set forth the operator or operators by dint of the application of a wrench to the upper ends of the 5 shafts 3 effect the upward traveling of the nuts 5 thereupon. This motion of the nuts is necessarily the motion of the platform as both are positively and securely united. When a desired height is reached the operators descend into the lower compartment of 10 the car and disengage the supports from their rest between the channel beams. The standards 12 are lowered until contact with the floor is had whereupon bolts or suitable 15 fastening means are passed between the apertures 10 and 13 thus securing the supports in firm position for sustaining the weight of the deck. When all of the supports are in position the weight is eased off 20 the shafts 3 and devolves upon the supports.

I desire it to be understood that slight changes in the construction and in the arrangement and combination of the several parts may be resorted to without departing 25 from the spirit of my invention provided such changes fall within the scope of the appended claim.

Copies of this patent may be obtained for five cents each, by addressing the "Commissioner of Patents, Washington, D. C."

Having thus fully described my invention what I claim as new and desire to secure by Letters Patent is:—

In a stock car structure, a stock car body, a vertically movable deck therefor having lower channel shaped portions, threaded deck elevating and guiding rods rotatively journaled on said car body, nuts carried by 30 the deck and having threaded engagement with said rods for elevating the deck on rotation of said rods, longitudinally extensible supports pivoted within said channel portions and proportioned to be frictionally held therein at least flush above the lower 35 margins of said channel portions, and a device for each support for locking the same in different extensible adjustments when the supports are withdrawn from said 40 channel portions into vertical positions for supporting the deck, substantially as described.

In testimony whereof I have affixed my signature in presence of two witnesses.

ROBERT H. CLYMER.
